UNITED STATES PATENT OFFICE

168,001

STOOL

Albert Sachs, Chicago, Ill.

Original application February 20, 1952, Serial No. 18,598. Divided and this application July 30, 1952, Serial No. 20,811

Term of patent 3½ years

(Cl. D15—8)

To all whom it may concern:

Be it known that I, Albert Sachs, a citizen of the United States, residing at Chicago, in the county of Cook and State of Illinois, have invented a new, original, and ornamental Design for a Stool, of which the following is a specification, reference being had to the accompanying drawing, forming part thereof.

In the drawings:

This application is a division of my co-pending application, Serial No. D.18,598, filed February 20, 1952.

I claim:

The ornamental design for a stool, substantially as shown.

ALBERT SACHS.
